BENCH VISE

Filed May 21, 1929

UNITED STATES PATENT OFFICE

GUS O. DANIELSON, OF CLARKIA, IDAHO

BENCH VISE

Application filed May 21, 1929. Serial No. 364,773.

My present invention relates to an improved bench vise of the screw operated type utilizing a stationary jaw and a movable jaw, together with adjustable connecting keys for the jaws by means of which an approximate adjustment of the movable jaw may be secured prior to the clamping operation by the screw. The primary object of my invention is the provision of a device of this character that is comprised of a minimum number of parts to insure simplicity in construction and operation of the device, and to provide a strong, durable and rugged clamp for the work. Due to the simplicity of construction and arrangement of the parts they may readily be assembled, and with equal facility the parts may be dissociated if and when desired for storage or for shipping.

The invention consists in certain novel combinations and arrangements of parts as will hereinafter be more fully described and claimed. In the accompanying drawings I have illustrated one complete example of the physical embodiment of my invention wherein the parts are combined and arranged according to the best mode I have thus far devised for the practical application of the principles of my invention.

Figure 1 is a perspective view of a bench equipped with the device of my invention, and showing a wood strip retained on the bench, for planing. Figure 2 is a perspective view of one of the adjustable keys. Figure 3 is a vertical sectional view at line 3-3 of Figure 8. Figure 4 is a perspective view of the stationary jaw and Figure 5 is a perspective view of the movable jaw. Figure 6 is a bottom plan view of a stop plate forming part of an accessory of the vise. Figure 7 is a perspective view of a detent used on the work in connection with the bench-stop. Figure 8 is a perspective view of the vise with the bench-stop forming a part thereof.

In Figure 1 I have illustrated a usual type of work bench B with a wood strip W secured thereon in proper position for planing, and the vise of my invention is utilized with associated parts for this purpose.

The vise comprises a stationary member and a relatively movable and adjustable member, the former being a flat plate 1, vertically arranged and provided with screw holes 2 for attachment to the side of the bench, as indicated in Figure 1. Near the upper end of the plate a screw hole 3 is provided at its center, and this upper portion of the plate is fashioned as a stationary jaw 4. The movable member comprises a flat metal plate 5 disposed, normally, in parallelism with the stationary plate and fashioned at its upper end with a jaw 6 complementary to the jaw 4 of the stationary plate.

The work is clamped between the movable jaw and the stationary jaw by means of a screw 7 that is threaded in the hole 3 of the stationary jaw and has a journal bearing 8 in the bearing hole 9 of the movable or clamping jaw, the holes 9 and 3 being alined to maintain the screw in normally horizontal position. The screw has an enlarged head 10 exterior of the movable jaw and the journal or reduced portion 8 of the screw has a loose fit in its bearing hole 75 to permit the necessary play of the movable jaw on the screw. The usual cross bar 11 is carried in the head 10, and by means of the bar the necessary leverage may be obtained for screwing and clamping the work 80 between the jaws.

The plates and their jaws are normally held in parallelism, and a spring 12 coiled about the screw and interposed between the two jaws assists in releasing the jaws from the work after the screw has been turned to release the movable jaw.

The device is adjustable within a comparatively wide range for accommodating various widths or thicknesses of the work to be clamped, but in all adjustments, the jaws are maintained in parallelism for effectively clamping the work between them. The movable jaw may be adjusted with relation to the stationary jaw for the reception of the work, after which the screw is turned for the clamping action.

The plates 1 and 5, near their lower corners are provided with alined pairs of key-holes comprising a circular opening 13 and 100

an angular opening 14, both openings forming an inverted key-hole of the conventional type, and these key-holes as shown are alined in pairs, for the reception of a pair of keys 5 15. These keys are rugged and strong round bars, with spaced angular lugs 16 integral therewith, and between the lugs are formed spaced notches 17.

The keys are inserted in the inverted key-holes with the lugs alined with the angular holes 14, and in this position the keys may easily be slipped through the alined key-holes, or the keys may remain stationary while the movable plate is adjusted toward or from the stationary plate, the screw being adjusted also for this purpose. The notches are of a width to correspond to the thickness of the plates 1 and 5, and it will be apparent that when the proper adjustment of the movable plate is attained, the keys are turned, one to the right and the other to the left so that the notched portions of the keys engage the plates and the lugs at opposite sides of the plates also engage the latter to prevent longitudinal movement of the keys. Due to the presence of the row of lugs on the keys, the latter are held against accidental turning, as the lugs perform the function of a weight in holding the keys in the position of Figure 8. When the parts of the vise are to be separated, the lugs are turned up to aline with the angular holes 14, after which the keys may readily be withdrawn from the plates. The movable plate may thus approximately be positioned by the use of the keys for various widths of work, and then the screw is turned to clamp the work.

In connection with the stationary jaw I 40 utilize a holder 18 in the form of a plate adapted to rest on top of the bench top or table, and this holder is adjustable with relation to the stationary jaw in order that the vise may be dropped a little below the 45 top of the bench. For this purpose the holder has a pair of spaced arms 19 bent downwardly at right angles to the holder and inserted in dovetail grooves 20 in the back of the jaw 4. By means of screws in 50 the screw holes 21 of the holder, the latter is secured to the bench, and the upper part of the stationary plate, and its jaw, are securely anchored to the benchtop.

The holder is also utilized as a support for 55 a bench stop or stop plate 22, having end teeth 23 to engage the wood strip W; a longitudinal slot 24; and at its underside the stop plate has rack teeth 25 for engagement 60 with complementary teeth on the holder. A screw 26 is used to secure the stop plate in adjusted position, and the rear end of the strip W is retained by a U-shaped detent 27 having teeth 28, to be driven into the bench 65 top, and a resilient tongue 29 to lie on top

of the rear end of the wood strip during the planing operation.

Having thus fully described my invention, what I claim as new and desire to secure by Letters Patent is:

1. The combination with a fixed plate having a jaw and a key-hole slot, of a movable plate having a complementary slot and jaw, a clamping screw joining the jaws, and a key located in said slots, said key having spaced lugs and alternating notches for the purpose described. 70

2. The combination with a fixed jaw having a pair of inverted keyhole slots, a movable jaw having a pair of inverted keyhole slots, and a clamp screw, of a pair of keys in said slots, said keys having spaced lugs and alternating notches for the purpose described. 75

3. The combination with a fixed jaw having an adjustable attaching-holder, of a movable jaw and a clamping screw connecting said jaws, said jaws having pairs of alined inverted key-holes comprising a circular opening and an angular opening, keys in said key-holes comprising round bars, and a row of spaced lugs on each bar having spaced notches therebetween for the purpose described. 80

In testimony whereof I affix my signature. 85
